UNITED STATES PATENT OFFICE.

FURMAN HUFF, OF CALDWELL, KANSAS, ASSIGNOR OF ONE-HALF TO
S. M. SHAUL, OF CALDWELL, KANSAS.

BOLTLESS PLOWSHARE.

No. 827,729.

Specification of Letters Patent.

Patented Aug. 7, 1906.

Application filed March 30, 1906. Serial No. 308,923.

To all whom it may concern:

Be it known that I, FURMAN HUFF, a citizen of the United States, residing at Caldwell, in the county of Sumner and State of Kansas, have invented certain new and useful Improvements in Boltless Plowshares, of which the following is a specification.

This invention relates to plows, comprising novel means for detachably securing a share 10 to the moldboard to readily admit of quick detachment of said share after same has become worn and attachment of a new share in substitution therefor.

The invention resides in novel details of 15 construction, the operation and advantages of which will appear more fully as the description proceeds.

For a full understanding of the invention and the merits thereof and also to acquire a 20 knowledge of the details of construction of the means for effecting the result reference is to be had to the following description and accompanying drawings, in which—

Figure 1 is a perspective view of a plow-share in operative position including the mechanism embodying the invention. Fig. 2 is a rear elevation of the share. Fig. 3 is a section on the line X X of Fig. 1. Fig. 4 is a section on the line Y Y of Fig. 1. Fig. 5 is a 30 perspective view of the slide plate and adjacent parts separated. Fig. 6 is a section on the line Z Z of Fig. 1. Fig. 7 is a vertical section showing the socket in which the front end of the throat-plate is seated. Fig. 8 shows clearly the lug at the front edge of the moldboard which engages in the groove in the rear vertical portion of the share. Fig. 9 is a section on the line 9 9 of Fig. 2 looking upwardly.

40 Corresponding and like parts are referred to in the following description and indicated in all the views of the drawings by the same reference characters.

In the drawings, the numeral 1 designates 45 the moldboard, the numeral 2 the landside, the numeral 3 the share, and the numeral 4 a throat-plate by which the moldboard is connected with the landside and which co-operates with the share in an evident manner. 50 Suitable fastenings attach the parts 1, 2, and 4 together, said parts being designed to be secured permanently for all general purposes. The share 3 is formed with a vertical wing 5 at its lower end, constituting a continuation

of the landside 2, the rear end portion of 55 which is provided with a socket or recess 6 to receive the lower front end portion of the throat-plate 4, the latter being of somewhat angular form embodying a horizontal portion attached to the landside and a vertically-arranged portion secured to the moldboard. The front end of the throat-plate has a sort of wedging action in the socket or recess 6, fitting snugly therein in order to obviate looseness or play of the parts in actual use. A lug 60 7, projecting from the outer side of the throat-plate 4, is adapted to engage in a groove 8 in the rear edge portion of the share 3, so as to interlock therewith, the parts fitting snugly at this point also, so that the 70 outer face of the share will be flush with the outer side of the moldboard in the customary way.

As before premised, special means is provided for securing the share detachably to 75 the moldboard and other parts adjacent thereto. Such means is comprised in a slide-plate 9, mounted upon a bracket 10, attached to the inner side and upper portion of the moldboard 1. The bracket 10 merely consists of a plate having a flat longitudinal portion upon which the slide-plate 9 slides, a suitable fastening attaching the plate 10 to the moldboard. A brace 11 is attached at its lower end to the heel of the landside 2, 80 the upper end of the brace being attached by a fastening 12 to a guide-plate 13, secured to the plate 10 in spaced relation thereto. The slide-plate 9 moves between the guide-plate 13 and the bracket-plate 10, one end of the 85 guide-plate 13 being of U form in cross-section to direct the longitudinal movement of the slide-plate 9. The fastening 12 passes through the brace 11 and the plates 9, 10, and 13, the plate 9 being formed with a slot 90 14 longitudinally thereof to receive said fastening 12 and permit of the longitudinal movement of the plate by actuating means provided therefor. The front end of the plate 9 has a lateral lug 15 projected therefrom to enter an opening or recess 16 in the rear upper portion of the share 3. The rear end of the plate 9 has an opening 17 therein to receive an eccentric disk 18, which is adapted for rotation with a stub-shaft 19, secured 100 to a lever 20. The lever 20 operates in rear of the brace 11, and when pivotal movement is imparted thereto the eccentric disk 18 is 105

actuated to impart slidable movement to the slide-plate 9. When the lever 20 is moved downwardly, the slide-plate is drawn rearwardly, and the lug 15 having been previously engaged with the opening or recess 16 in the share 3 will thus positively pull said share rearwardly to cause the front end of the throat-plate 4 to move into the recess or socket 6 of the share and also to cause the lug 7 to enter the groove 8 in the share. This operation will firmly attach the share to the moldboard and throat-plate; but it will be readily seen that a simple upward movement of the lever will quickly release this part of the plow and permit of removal thereof when it is worn, so that it may be replaced without loss of time and labor.

Having thus described the invention, what is claimed as new is—

20 1. In a device of the class described, the combination of a landside, a moldboard, a detachable share, means for securing said share to the moldboard and adjacent parts, a slide-plate mounted upon the inner side of the moldboard and having means to engage the share, said slide-plate being provided with an opening in its rear end portion, guide means for the slide-plate, an eccentric disk operating in the opening of the slide-plate, 25 and a lever connected with said eccentric disk to actuate the same and impart slidable movement to the slide-plate.

2. In a device of the class described, the combination of a landside, a moldboard, a throat-plate connecting the landside and moldboard, a share provided with a socket to receive the front end of the throat-plate and having a groove in its rear portion, a lug pro-

jecting from the throat-plate to enter the groove in the share, and an operating device 40 applied to the moldboard and provided with means for connection with the share and positively cause the throat-plate and the lug of said throat-plate to engage with the share as specified.

3. In a device of the class described, the combination of a landside, a moldboard, a throat-plate connecting the landside and moldboard, a share provided with a socket to receive the front end of the throat-plate and having a groove in its rear portion, a lug projecting from the throat-plate to enter the groove in the share, a brace connecting the heel of the landside with the upper portion of the moldboard, a bracket-plate secured to the rear side of the moldboard, a guide-plate attached to the bracket-plate in spaced relation thereto, a slide-plate movable between the bracket-plate and the guide-plate and having a lug to engage the share, a fastening 60 passing through the upper end of the brace, the guide-plate, and the bracket-plate to secure said parts together, the slide-plate having a slot intermediate of its ends to receive said fastening and also having its rear end 65 provided with an opening, an eccentric disk arranged in the opening of the slide-plate, and an operating-lever connected with said disk to actuate the same and impart longitudinal movement to the slide-plate as specified.

In testimony whereof I affix my signature in presence of two witnesses.

FURMAN HUFF. [L. s.]
